TYPEWRITER BAIL

Ralph A. Maddox, Los Angeles, Calif.

Application February 2, 1950, Serial No. 141,907

2 Claims. (Cl. 197—138)

1

This invention belongs to that general class of devices known as typewriters and relates particularly to bails which are employed for holding down paper upon the main carriage roller. In some of the old typewriters, the bails are straight and have bail arms extending therefrom that are adapted to hold paper close to the main carriage roller, and these bails are generally supported at their ends by bearing holes in the top sides of the carriage. The bails of this invention are not straight, but are configurated and designed so that their ends are receivable in the same bearing holes which accommodated the old straight bails.

The invention also concerns the bail rollers which slide along the straight portions of the bail rods. The rollers comprise pliable cylinders, each cylinder having a coiled spring-like liner to which it is very snug, and a bearing of somewhat smaller diameter which has an angularly formed axis and a bore that is slightly larger than the bail rod diameter, this bearing preferably consisting of a coil spring-like element.

The invention has among its objects the production of a means of the kind described that is simple, durable and compact in structure, inexpensive to make and manufacture, dependable and efficient in use and service, and convenient to handle and install; devices that are pleasing and attractive in appearances and very satisfactory for use whenever and wherever found applicable.

Other objects, advantages and features of this particular invention will appear from a careful perusal of the accompanying drawings, the subjoined detailed description, the preamble of these specifications, and the claims appended hereto.

Below, applicant describes one of the preferable forms of his invention in order to teach the art and application thereof and show how to make and use it in combination with any device wherein sheets of material must be handled, but it is to be understood that the drawings and description thereof are not to limit the invention in any sense whatsoever except as the same may be limited by the prior art. Language employed herein is not to be construed as giving any unauthorized person or organization the right to make, use and/or sell the invention or its parts as herein disclosed.

In the drawings:

Figure 1 is a plan view of the invention showing its position upon a portion of a carriage of a typewriter; the scale employed is about one-half full size;

2

Figure 2 is a side elevational view of a portion of a typewriter carriage; the scale employed is about full size;

Figure 3 is an end elevational view of a pliable cylinder; the scale employed is about double size;

Figure 4 is a side elevational view of that shown in Fig. 3;

Figure 5 in double size scale shows an end elevational view of a coiled liner for the cylinder of Figs. 3 and 4;

Figure 6 is a side elevational view of that shown in Fig. 5;

Figure 7 is an end elevational view of a coiled bearing element adapted to telescope the liner shown in Figs. 5 and 6; this being shown also in double size scale;

Figure 8 is a side elevational view of that shown in Fig. 7;

Figure 9 in double size scale is an end elevational view of the entire bail roller;

Figure 10, double size scale, is a side elevational view of the coiled bearing in angular formation, this shows how the bearing of Fig. 8 is bent before it is slid onto the bail rod.

The invention, as illustrated, is shown in combination with an office desk type "Underwood" typewriter. Since this invention is concerned only with the upper portion of a typewriter, that is, when the invention is employed with a typewriter, only the essential parts of the typewriter are illustrated and recited. Such a typewriter machine has a main paper roller 1 that is supported by end spindles 2 and 3 that have proper bearing in the end plates 4 and 5, respectively. The top and outer portions of the end plates are covered by a suitable cover-plate, these cover-plates being indicated by the reference characters 6 and 7. The back paper feed-plate is indicated at 8.

As shown in Fig. 2, the cover-plate 7 has been omitted in order to better show the bearing bore 9; there being a similar bore 10 in the other end-plate 4. A small tab portion 11 of the end-plate 45 5 has been bent downwardly to accommodate one end of a coiled tension spring 12.

The bail consists of a straight portion of round rod 13, one end being bent at 14 and the very end having another bent portion 15 which passes through the bore 10. The other end of the bail has a bent portion 16 and then an outwardly bent portion 17 which passes through the bearing bore 9, this end is further bent to form the downwardly directed leg 18 from which there is 55 the forwardly bent portion 19, the very end of

which serves as a stop to limit the upwardly motion of the bail in that such bails are raised in order to insert paper and for other purposes which are well known to operators of such machines. The lower end of the spring 12 is fixed to the under portion of the headed rivet 20. Obviously, the purpose of the spring is to keep the bail rod downwardly and constantly urged against the large roller, but when the bail is lifted to its vertical position, this same spring maintains same in this position until forced downwardly.

As in usual practice, the bail 13 is provided with the pair of slideable small rollers 21 and 22. As can be seen, by reference to Figs. 3 to 10, each small roller has an outer cylinder 23 which is snugly forced onto a coiled spring element 24, and this element telescoped by a smaller spring element 25. The ends 26 of this smaller element are bent, as indicated in Fig. 9 so that the larger spring element 24 will be maintained within the confines of its ends in that there is sufficient clearance between the two spring elements so that the larger one will readily roll around the smaller one. In order to create sufficient friction between the smaller spring and the bail rod so that the small rollers 21 and 22 can be set in any desired position along the bail rod, the smaller spring elements are bent as shown in Fig 10 prior to being placed onto the rod 13. For purposes of smoother rolling action, the two spring elements 24 and 25 are wound in opposite directions, however, they may be wound in the same direction and still be useful and have free action of rotation, but it is preferred to wind them in opposite direction in order to avoid any likelihood of the convolute of one spring becoming trapped in the grooves between the convolutes of the other spring.

When the bail is assembled and placed a certain procedure is followed. The first step is to take the bail rod 13 without its small rollers and insert the end 15 through the hole 9. The second step is to force a single bent spring element 25 onto the rod end 15 and to its position near the end portion 16. Third step is to force the spring 24 onto the rod and over the top of spring 25, and the final step is to pass the rubber cylinder 23 onto the rod and force it onto the large spring 24.

It is, of course, understood that various changes and modifications may be made in the details of form, style, design, and construction of the whole

or any part of the specifically described embodiment of this invention without departing from the spirit thereof in that such changes and modifications are considered as being within the scope of the following claims:

I claim:

1. In a bail device for typewriter rollers, the bail comprising a straight portion of rigid rod with end extensions rearwardly directed when the bail is in its normal downward position, one of the extensions having a turned portion which forms a bearing and is adapted to enter a bore, the other extension having a laterally directed short portion for positioning in a fixed supporting bore, this latter extension from its end having a downwardly directed crank-like portion with a spring attached thereto for holding the crank portion in either a downward position or in an upward position, a stop integral with the crank-like portion to limit the upward movement of the straight rod portion, a pair of small rollers on the straight rod portion, each small roller consisting of an outer surface and inner surface which has a liner snugly engaged therewith and a bearing element adapted to slide along the bail rod, and means maintaining the liner in position on its bearing element.
2. The device recited in claim 1 wherein the bearing element is a coiled spring wire and the liner is a coiled spring wire wound in the opposite direction to that of its bearing element.

RALPH A. MADDOX.
